UNITED STATES PATENT OFFICE.

JOHN H. CONNELL, OF STAUNTON, VIRGINIA.

RAILROAD-TIE.

SPECIFICATION forming part of Letters Patent No. 595,452, dated December 14, 1897.

Application filed September 20, 1897. Serial No. 652,320. (No model.)

To all whom it may concern:

Be it known that I, JOHN H. CONNELL, a citizen of the United States, residing at Staunton, in the county of Augusta and State of Virginia, have invented certain new and useful Improvements in Railroad-Ties; and I do declare the following to be a full, clear, and exact description of the invention, such as will enable others skilled in the art to which

it appertains to make and use the same.

My invention has relation to railroad-ties; and it has for its object to provide a durable, indestructible, and non-combustible tie which may be placed upon the market at a minimum cost and by means of which the rails may be firmly supported and prevented from springing therefrom.

With this object in view the invention consists in certain features of construction and combination of parts, which will be herein-after fully described and claimed.

In the accompanying drawings, Figure 1 is a perspective view of my improved railroad-tie. Fig. 2 is a similar view of the parts forming the shell of the tie separated, and Fig. 3 is a cross-sectional view.

In the drawings the tie shown consists of a metallic shell comprising four sections—the side sections 1 and 2 and the top and bottom sections 3 and 4, respectively. Each side section consists of a longitudinal strip *a*, bent at right angles to form the end *b* and then parallel with the strip *a*, as shown at *c*. These sections are brought together, with the longitudinal strip *a* of one section abutting against the end of the short strip *c* of the other section, thus forming a shell. The bottom section 4 is now placed in the shell and a plastic material, preferably cement, is poured in the shell thus formed. The top 3 is now placed in position and a vertical bolt 5 inserted through registering apertures 6 and 7 in the top and bottom pieces, while a bolt 8 is inserted through registering apertures in the side sections of the shell. This construction provides a strong and powerful tie, one that is perfectly proof against being burned by the dropping cinders of passing locomotives, and one whose life is greatly increased over that of the ordinary wooden tie.

In order to hold the rails firmly to the tie, I provide means consisting of a head 9, bolted at each end to the tie and adapted to fit against

the outer side of the web of the rail under its tread. At each side of the head are arranged two lugs 10, which have plates 11 bolted to the sides of the rail. These lugs have inclined under edges that engage the inclined upper surface of the base of the rail and serve as auxiliaries to the heads in holding the rail to the tie. Opposite to the heads are arranged lugs 13, that coat with the heads and are provided with inclined outer faces that engage the upper side of the base of the rail in a manner similar to the lugs aforesaid. These lugs 13 are bolted to the tie.

From the foregoing description, taken in connection with the accompanying drawings, the construction and advantages of my invention will be readily understood without requiring an extended explanation.

While the initial cost of the tie may be somewhat greater than that of the ordinary wooden tie, it will be perceived that in the end great saving will be effected by its employment, inasmuch as it will last an indefinite period of time and will not be influenced by the changes in temperature and weather.

Having thus described my invention, what I claim, and desire to secure by Letters Patent, is—

1. A railroad-tie consisting of a shell composed of side sections, each section composed of a long and a short parallel strip connected by an end strip, said sections having their ends connected in break-joint fashion, a bottom piece, a top piece, a filling of plastic material, and means for connecting the sections, substantially as set forth.

2. A railroad-tie consisting of a shell composed of side sections, each section composed of a long and a short parallel strip connected by an end strip, said sections having their ends connected in break-joint fashion, a bottom piece, a top piece, a filling of plastic material, and vertical and transverse bolts, the former connecting the top and bottom pieces and the latter the side sections, substantially as set forth.

In testimony whereof I hereunto affix my signature in presence of witnesses.

JOHN H. CONNELL.
